ATTORNEY

UNITED STATES PATENT OFFICE

CHARLES J. DEL'MARMOL, OF FRANKFORD, PENNSYLVANIA.

REPRODUCER.

1,424,087.

Specification of Letters Patent. Patented July 25, 1922.

Application filed September 6, 1921. Serial No. 492,775.

To all whom it may concern:

Be it known that I, CHARLES J. DEL'MARMOL, a citizen of the United States, residing at Frankford, in the county of Philadelphia, 5 and State of Pennsylvania, have invented new and useful Improvements in Reproducers, of which the following is a specification.

This invention relates to reproducers for 10 talking machines and similar devices for the transmission of sounds and it has for its primary object to provide a reproducer which will effectively reproduce sounds or sound waves, whilst at the same time the 15 volume of sound so reproduced will be considerably increased.

Another object of this invention is the provision of a reproducer of the type above referred to which is exceptionally light in 20 weight whereby friction on the records is reduced to a minimum.

A further object aimed at is the provision of a reproducer characterized by an effective insulation of the stylus bar and its 25 mounting from the main or body portion of the reproducer, whereby foreign noises and scratchy sounds due to metallic contacts are obviated and prevented:

A still further object of this invention is 30 the provision of a reproducer, which is simple in construction, neat in appearance, cheap to manufacture, effective in use, not liable or susceptible to derangement, and by the employment of which tonal reproduction 35 is raised to a very high degree of perfection.

With the foregoing and other objects in view as will become more apparent as the following description proceeds, this invention consists essentially of a reproducer having 40 a resonating chamber in front of the diaphragm proper and valvular outlets therefrom disposed in eccentric relation to said diaphragm.

In the further disclosure of the invention 45 reference is to be had to the accompanying sheet of explanatory drawings constituting a part of this specification and in which like characters of reference designate the same or corresponding parts in all the views.

50 Figure 1— is a fragmentary side view of portion of an ordinary phonograph and tone arm having my improved reproducer applied thereto, the latter being shown from a frontal aspect.

55 Figure 2— is an enlarged side elevation

of my improved reproducer detached from the tone arm.

Figure 3— is a rear view of the same; and, Figure 4— is a central transverse section of the same.

Referring more particularly to the view the turntable of an ordinary phonograph machine is designated by the reference character 5 and on which the record 6 to be played or reproduced is seated in the well 65 known way, whilst a fragmentary portion of the tone arm is indicated by the numeral 7.

Arranged for frictional connection on the end of the tone arm 7 is my improved reproducer 8 which consists essentially of a 70 main or cylindric body portion 9 having a relatively thick crescent-shaped enlargement 10 intermediate its ends and extending substantially three parts of the way around its bore and from the front or outer face where- 75 of are stepped borings 11, 12 and 13 axially eccentric with respect to the center of the cylindric body portion 9. It is to be parti- cularly noted that the boring 11 constitutes the housing for the hard rubber or other 80 appropriate material diaphragm 14 which is supported therein between insulating washers 15, 16 and firmly clamped by a locking ring 17 held in place by screws 18 in the well known ways. The inner borings 12, 13 85 respectively, provide a clearance space 19 at the back of the diaphragm and a sound outlet 20 concentric with the latter and at the back of the rigid diaphragm portion or wall 21 there being provided a tubular part or 90 tone-arm connecting means 22 appropriately lined with a bushing of rubber 23 whereby the reproducer 8 is frictionally held on said tone arm 7. It is also to be observed that the back of the reproducer 8 is dished or re- 95 cessed at 24, whilst the forward part being similarly recessed but to a much larger extent provides a sound amplifying box or res- 100 onating chamber 25 which is closed in by a thin mica or the like diaphragm 26 held in place by insulating washers 27, 28, and a 105 bezel ring 29 circumferentially perforated at 30 to reduce weight as well as to aid in gripping the adjoining washer 28 and prevent its movement relative thereto or with respect to the diaphragm 26.

Substantially all around the circumferential wall of the sound amplifying box or resonating chamber 25 and at equal intervals are apertures or holes 31, the outer ends 110

whereof are slightly flared as shown. Similarly the aforesaid crescent-shaped enlargement 10 is drilled or otherwise formed to provide a series of cylindric-shaped recesses 32 which connect into the aforementioned amplifying box or resonating chamber 25 by pin or small holes 33.

Connected centrally of the diaphragm 14 is the transmitting post 34 which passes through a bore 35 in the main or body portion 9 in the well known way, and it is anchored to said body portion 9 by means of pivot studs or knife-edges 36 contact being maintained by screws 37 between the heads whereof and the bridge 38 are interposed compression springs 39. The stylus or needle 40 is clamped in place by means of the usual thumb or knurled screw 41.

20 In use it will be clearly seen that as the stylus or needle 40 travels over the rotating record 6 the sound vibrations will be conducted by the transmitting post to the diaphragm 14, and by reason of the peculiar nature and formation of the reproducer will be partly distributed between the sound amplifying box or resonating chamber 25 as well as to the tone arm 7, the cylindric shaped recesses 32 and holes 31 serving as vents for 36 the escape of sound.

From the foregoing description it will be apparent that by my invention there is provided an exceedingly light weight reproducer which eliminates to a great extent all friction on the records, with a consequential reduction in wear and tear to the motor as

well as assuring its economical use. Still further due to the lightness of the reproducer an economy in use of needles is brought about.

Whilst there has been shown and described one practical embodiment of the invention it will be perfectly clear that the same is susceptible of detail modification and variation without in any way departing from its essential features, and it is hereby intended to include all such reasonable modifications as fairly fall within the scope of the appended claims.

Having described my invention, what I claim as new, and desire to secure by Letters Patent is:

1. A sound box comprising a cylindric body, an apertured wall closing one end of said body and formed with a peripheral enlargement, a diaphragm, a supplemental diaphragm closing the other end of the cylindric body and forming an amplifying chamber, said enlargement being apertured and said cylindric body being apertured around the amplifying chamber.

2. A sound box comprising a cylindric body, an apertured wall closing one end of said body and formed with a peripheral enlargement, a diaphragm, a supplemental diaphragm closing the other end of the cylindric body and forming an amplifying chamber having escape openings in the wall thereof.

In testimony whereof I affix my signature. 70

CHARLES J. DEL'MARMOL.
